CHARLES A. MORSE AND EDWIN H. BELL, OF CHICAGO, ILLINOIS.

TIE-PLATE.

1,246,980.

Specification of Letters Patent. Patented Nov. 20, 1917.

Application filed May 5, 1917. Serial No. 166,516.

To all whom it may concern:

Be it known that we, CHARLES A. MORSE and EDWIN H. BELL, citizens of the United States, and residents of Chicago, in the county of Cook and State of Illinois, have invented certain new and useful Improvements in Tie-Plates; and we do hereby declare that the following is a full, clear, and exact description thereof, reference being had to the accompanying drawings, and to the letters of reference marked thereon, which form a part of this specification.

This invention relates to improvements in tie plates and consists of the matters herein-after described and more particularly pointed out in the appended claims.

The object of our invention is to produce a tie plate which is so constructed with a minimum of metal that it is capable of withstanding the great strain imposed upon it in use without buckling or breaking. Another object of the invention is to provide a tie plate which may be easily made by the rolling process and which, when in track, will not tip or creep in the direction of the rail due to the wave motion thereof under load of passing trains.

These objects, together with the advantages of the improved tie plate, will more fully appear as we proceed with our specification.

In the drawings:

Figure 1 illustrates in a perspective view, a tie plate made in accordance with our invention.

Fig. 2 is a view in side elevation thereof, on an enlarged scale.

Fig. 3 is a view illustrating a transverse section through the tie plate, the plane of the section being indicated by the line 3-3 of Fig. 2.

Fig. 4 is a top, plan view of the tie plate on a smaller scale.

Referring now in detail to that embodiment of our invention illustrated in the accompanying drawings:—5 indicates the tie plate as a whole, which, as shown, is rectangular in plan and is longer than it is wide. Near the outer end 6 of the tie plate, and on its top surface, is formed a transversely extending upright flange which provides a rail abutting shoulder 7 adapted to be engaged by the outer edge of a rail base 8. Beyond said flange, said outer end of the tie plate is tapered in the usual manner.

On the top surface of the tie plate are a

plurality of transversely extending ribs, 9, 10 and 11 respectively. These ribs are parallel with the shoulder 7, and provide longitudinally spaced seats on which the rail base is adapted to rest. The intermediate rib 10 is separated or spaced from the end-most ribs 9 and 11, respectively, by comparatively deep grooves, 12, 12, which are of a width substantially equal to the width of the intermediate rib 10.

Each rib 9, 10 and 11 has a cambered or a convexed surface 9^a, 10^a, 11^a respectively, which terminates short of the ends of each rib to provide flat end parts 9^b, 10^b, 11^b, on said ribs, the higher or thicker portions of said ribs being located on the longitudinal median line of the tie plate as a whole. The inner end 13 of the tie plate tapers off in thickness from the rib 9, in the same manner as the outer end 6 of said plate, before described.

Upon the bottom surface of the tie plate, preferably below and parallel with the end-most ribs 9 and 11, are provided more or less sharpened flanges 14 which are adapted to engage and penetrate the tie in a manner preventing endwise slipping of the plate as a whole upon the tie.

When the tie plate is in track, the rail base 8 rests upon the top parts or summits of the cambered surfaces 9^a, 10^a, and 11^a, respectively, of the ribs 9, 10 and 11, the outer edge 8^a of the rail base being engaged or abutting against the rail shoulder 7. When one of the marginal or side edges 15 is depressed, the tendency would be to cause the other side edge 15 to be raised; but it is apparent that the rail base 8 cannot, normally, engage or bear upon the lateral, marginal edges 15 of the plate because of the arcuate or cambered surfaces thereof which prevent tendency of the plate tipping in a direction parallel to the rail, and consequent loosening of the tie plate from its engagement with the tie.

Compression strain due to the weight of the load is transmitted or imparted to the tie plate only on its longitudinal median line and in the vicinity thereof, where the tie plate is the thickest and where our plate is most capable of withstanding such load without buckling and breaking.

Wave motion of the rail under the load of passing trains will not tend to dislodge or dislocate the tie plate from its seat on the tie nor permit the engagement of the rail

with the lateral edges of the plate, because of the cambered top surfaces of the ribs 9, 10 and 11, which are curved in a direction longitudinally of the rail and parallel to the wave motion thereof. The ribs 9, 10 and 11 being in a sense trusses, afford additional strength to the plate and act to resist any tendency to longitudinal or creeping movement of the plate on the tie, which often occurs where the plates are of the same substantial thickness throughout.

All tendencies of moisture or dirt to collect or settle on said cambered ribs is minimized by the camber or arcuate surfaces and by the location of grooves or channels between them, thus permitting a constant circulation of air beneath the rail in the direction of the wave motion. Consequently the plate is kept dry and free from rust. This is important because the drippings from refrigerator cars has an extremely deleterious effect upon metal and as these drippings can be taken care of by proper drainages and evaporation through air circulation, these injurious effects cannot exist to any appreciable extent in our plate.

Our improved tie plate possesses many other advantages. It may be produced by the "rolling" process, the strip being rolled or formed in a direction parallel to the various ribs thereon and to the shoulder 7. Each tie plate blank of said strip is separated or cut from its adjoining neighbor on a line passing between the adjacent ends of the cambered ribs, said line of shearing being through the flattened and somewhat thinner parts 9^b, 10^b and 11^b of the tie plate blank. Thus even though inaccuracies occur in the rolling of the strip, the average width of the plate will exist between the ends of the cambered ribs and in no instances will there be a wastage in cutting the strip because of shearing the same through some part of the cambered surfaces of the ribs.

While in describing our invention, we have recited certain specific details of construction, arrangement and form of parts, we do not wish to be limited thereto except as may be pointed out in the appended claims.

We claim as our invention:

1. A tie plate having a plurality of ribs on its top surface providing spaced seats for a rail, said ribs being cambered in a direction parallel with said rail, and having flattened parts at the ends of the camber.

2. A tie plate having a flat bottom surface and a plurality of transverse ribs on its top

surface which provide seats for a rail, said ribs being spaced or separated from each other by means of a channel or groove, and being cambered in a direction parallel with the rail, and flattened end parts on each rib parallel with the bottom surface of the tie plate.

3. A tie plate having on its top surface a plurality of transversely extending ribs providing seats for a rail base, each rib being thickest on the longitudinal median line of the plate and being curved downwardly and outwardly toward the lateral edges thereof, but terminating short of said edges, each endmost rib being separated from the adjacent or intermediate rib by a channel of a width approximating the width of the said adjacent or intermediate rib, and a rail abutting shoulder parallel with and along one edge of one of said endmost cambered ribs.

4. A tie plate having on its top surface a plurality of transversely extending ribs providing seats for a rail base, each rib having a cambered top surface which terminates short of the lateral edges of the plate, a groove or channel separating each endmost rib from the adjacent or intermediate rib, a rail abutting shoulder on the top of said plate along one edge of and parallel with one of the endmost cambered ribs, and flanges, more or less sharpened, on the bottom surface of the plate for engagement with a tie.

5. A tie plate having on its top surface a plurality of transversely extending ribs providing seats for a rail base, each rib having a cambered top surface which terminates short of the lateral edges of the plate, a groove or channel separating each endmost rib from the adjacent or intermediate rib, a rail abutting shoulder on the top of said plate along one edge of and parallel with one of the endmost cambered ribs, and flanges, more or less sharpened, on the bottom surface of the plate immediately beneath and parallel with the endmost rail supporting cambered ribs.

In testimony that we claim the foregoing as our invention we affix our signatures in the presence of two witnesses, this 3rd day of May, A. D. 1917.

CHARLES A. MORSE.
EDWIN H. BELL.
